SHINGLE

Harry H. Honigbaum, New York, N. Y.

Application August 22, 1930, Serial No. 477,008

2 Claims. (Cl. 108—33)

This invention relates to shingles. While the invention may be incorporated in shingles of any material, it is particularly useful in connection with so-called composition shingles. Furthermore, the invention may be employed with shingles of various shapes, but it is especially intended for the diamond or hexagonal form of individual shingle.

The object of the invention is to provide a shingle which may be manufactured with great economy and one which will embody pronounced practical advantages. Speaking generally, the shingle of this invention comprises a body and one or more members made separate from the body and secured directly to the under side of the body. This member or members are provided with one or more extensions which project laterally beyond the contiguous edges of the body of the shingle and are adapted to extend beneath the edges of shingles of the next preceding course.

A novel feature of the invention resides in providing an exposed portion of the edge of the shingle with a flange turned at right angles to the body of the shingle and extending downwardly. This flange may be of any desired height so that it imparts to the shingle the optical effect of appreciably increased thickness. So far as I am aware, shingles with one or more turned down edges or vertical flanges, such as I have described are distinctively novel in this art, and my experiments therewith have shown that it imparts to a roof of these shingles an unusually pleasing and rich effect, while materially reinforcing the shingle.

Features of the invention, other than those specified, will be apparent from the hereinafter detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is a fragmental perspective view showing the under side of the weather end of a diamond shaped shingle provided with the lateral projections and the downwardly extending flange to which I have referred.

Figure 2 is a section on the line 2—2 of Fig. 1.

Figure 3 is a perspective view of the front or exposed face of a modified form of shingle made according to this invention.

Figure 4 is a section on the line 4—4 of Fig. 3.

Figures 5 and 6 are perspective views of the

under sides of further modified forms of shingles embodying the invention.

Figure 7 is a section on the line 7—7 of Fig. 6.

Figure 8 is a perspective view showing three shingles according to the present invention laid on a roof in the manner in which they cooperate to form a weather-proof covering therefor.

Referring to the drawings, and especially to Figures 1 and 2, 1 indicates the body of a shingle. This body is a flat body provided with a weather end 2 and lateral edges 3 which adjacent the weather end are exposed when the shingle is laid. Extending across the body 1 is a member 4. This member is made separate from the body and is secured to the under side of the shingle as shown. It may be of any suitable material and may be secured to the shingle body in any appropriate way. If made of non-metallic material, it may be adhesively secured to the body or may be stapled, riveted or fastened thereto in a permanent manner most convenient. If made of metal, prongs 5 punched from the middle may be forced through the material as shown in Fig. 2 to secure the member to the body. Any number of these prongs may be employed. The member 4 illustrated in these figures is of substantially U-shaped cross section with one flange 6 fastened to the body and the other flange 7 extended beyond the edges 3 of the body to form laterally projecting wings which may be either straight as shown or the edges 8 may be tapered, so as to converge toward one another in a downward direction as indicated in the other figures of the drawings.

The portions 9 which extend beyond the edges 3 form retaining members which are adapted to extend beneath the contiguous edges of adjacent shingles of an underlying course to hold down the weather end of the shingle 1, so as to keep it from flapping or curling. It will be noted that the extensions 9 are spaced above the back of the body in Fig. 1, thereby facilitating the laying of the shingle. At the weather end of the shingle is a substantially right angular flange 10 as shown.

It is within the purview of the invention to form smaller flanges along the edges 3 and these flanges may extend for the whole or a part of the length of these edges, so as to give the effect of greatly increased thickness of the body. The formation of flanges as stated along one or more of the edges of the shingle body is not restricted to the structure of Fig. 1, but may be used on any shingle without departing from this invention as I consider this feature per se highly novel and important.

In the structure shown in Figs. 3 and 4, the shingle body 11 is shown as provided on its back and near its weather end 12 with a transversely extending member 14 secured to the body by means of punched out prongs 15. The extending portions 19 are hooked upwardly to provide inclined edges 18. Figure 4 very clearly shows the manner of attaching the member 14 to the shingle body 11. This form of attachment, however, while particularly adapted for metal members is not the exclusive way of attaching them. Any other appropriate form of attachment may be employed.

The structure of Fig. 5 differs from the structure of Fig. 3 primarily in that the members 24 which correspond to the members 4 and 14 are made in two distinct and separate parts which are individually secured to the back of the shingle and have hook shaped extensions 29 which extend beyond the edges of the shingle body 21.

The structure of Figs. 6 and 7 is similar to the construction of Fig. 3, except that the member 34 is made relatively wide and is secured, for example, as by stapling, an adhesive, or in any other suitable way within the confines of the line 40, so as to leave the lower edge of said member free to bend outwardly as indicated at 41 in Fig. 7. The member has the hooked shaped extensions 39 as shown. The practice, the members 4, 14, 24, and 34 may be made either metallic or non-metallic. If metallic they may be made up from scrap stock in a convenient and economical way. If made up of non-metallic material, such, for example, as asbestos or composition roofing material, scrap or waste can be employed in their manufacture, and if of a non-metallic material, these devices may be readily adhesively secured in place on the back of the body as described. The edges of all of the shingles may be plain as stated or two or more of them may be flanged as I have described. With the flanged construction, the rearwardly offset hooked wings are advantageous in facilitating the laying of the shingles while making it unnecessary to unbend or flatten down the flanges along the edges of the shingle. If flanges are utilized in the structures of Figs. 3 and 5, it may be desirable if the flanges are relatively deep to rearwardly offset the extensions 19 and 29, so as to permit these extensions to be introduced beneath the contiguous edges of underlying shingles without crushing the flanges of the shingles of either course.

I have hereinbefore referred to the flanges 2. These flanges are formed by bending down one or more of the edges of the shingle and in a composition shingle this may be readily accomplished while the shingle is hot and in the course of manufacture. The several members 4, 14, 24 and 34, may be conveniently in practice made from relatively cheap or waste material. This is particularly true where these members are of composition or asbestos material. The cost of the members therefore when made of such materials is practically nil, as the stock employed therein would otherwise be thrown away.

In Figure 8, I have shown how shingles are laid to form a roof embodying the present invention. Three courses of shingles are indicated in this figure. The shingle 11 is of the last laid course. The shingles 11a are of the next subjacent course and the shingle 11b indicated in double dot and dash lines in this figure is of the course underlying said subjacent course. The shingles shown in this figure are of the type illustrated in Figure 3 of the drawings provided

with a turned down flange at the weather end, this flange 2 extending downwardly and substantially bridging the space between the edges of the subjacent shingles 11a and terminating in a downwardly facing natural cut edge bearing against the shingle 11b of the course underlying said subjacent course. The wings 19 hold down the shingle 11 so that the under face of said shingle is in face abutting relation with the shingles 11a and at the same time force the lower natural cut edge of the flange 2 against the face of the shingle 11b.

A pronounced advantage of the structure of this invention resides in its marked economy and the further fact that no part of the body of the shingle is cut away and there need be absolutely no waste in the manufacture of the shingle. Practically every portion of the material used for the manufacture of the body of the shingle may be utilized as there need be no actual waste in the cutting and the little waste which may occur could be used in making the anchorage members to which I have referred.

The present invention therefore is unusually economical to manufacture and may be sold at a relatively low price. Furthermore the forms of anchoring members are such that they may be readily slipped under the edges of shingles of an underlying course because they lie below the shingle on which they are mounted and thus radially line up with the shingles under which they extend. Furthermore, they do not tend to bend or distort the shingle on which they are attached, but permit said shingle to lie flat on the roof. The present invention contemplates not only the shingle construction to which I have referred, but also a roof embodying shingles made in accordance with this invention.

The foregoing detailed description sets forth the invention in its preferred practical forms, which are shown as illustrative only, the invention being fully commensurate with the appended claims.

By the term "natural cut", as used in the appended claims, I mean the raw edge of the composition material which is produced when this material is blanked out from roll stock by dies after the manner generally practised in this art.

Having thus fully described the invention, what I claim as new and desire to secure by Letters Patent is:

1. A roof embodying composition shingles laid in successive courses in overlapping staggered relation, each shingle comprising a substantially flat body having sheer lateral edges which overlie in close contiguous relation the bodies of adjacent shingles of the next subjacent course and converge toward the weather end of the body, said body being provided along said weather end with a flange extending downwardly and substantially bridging the space between the edges of said subjacent shingles and terminating in a downwardly facing natural cut edge bearing against the face of a shingle of the course underlying said subjacent course, and wings secured to the under side of the body adjacent the flange and projecting in opposite lateral directions in a plane below the plane of the body and extending beneath the bodies of said subjacent shingles to hold down the shingle body and maintain the downwardly facing natural cut edge of said flange in position to bear upon the shingle of said underlying course.

2. A composition shingle comprising a body provided along its weather end with a flange ex-

tending in a downward direction in substantially right angular relation to the body for a distance below the body approximately equal to the thickness of the body and there terminating in a 5 downwardly facing natural cut edge, said body having unobstructed sheer lateral edges which diverge from the flanged weather end, whereby when a plurality of such shingles are laid upon a roof, the said body is adapted to lie flat and 10 in facial engagement with the underlying portions of the shingles of the subjacent shingle course with the downwardly facing edge of said flange in engagement with the face of a shingle of the course underlying said subjacent course, and wings secured to the under side of the body adjacent the flange and projecting in opposite lateral directions in a plane below the plane of the 80 body and extending beneath the bodies of said subjacent shingles to hold down the shingle body and maintain the downwardly facing natural cut edge of said flange in position to bear upon the shingle of said underlying course. 85
